UNITED STATES PATENT OFFICE.

LEWIS J. DE HOLCZER, OF CHICAGO, ILLINOIS.

DESIGN FOR A PNEUMATIC TIRE.

Application filed September 24, 1924. Serial No. 10,892. Term of patent 14 years.

To all whom it may concern:

Be it known that I, LEWIS J. DE HOLCZER, a citizen of the United States, residing in Chicago, in the county of Cook and State of Illinois, have invented a new, original, and ornamental Design for Pneumatic Tire, of which the following is a specification, reference being had to the accompanying drawing, forming part thereof.

In the drawing: Figure 1 is a developed plan of a fragment of a pneumatic tire, showing my design, and Fig. 2 is a section taken on line 2—2 of Fig. 1.

I claim:

The ornamental design for a pneumatic tire as shown.

LEWIS J. DE HOLCZER.
